HUMIDIFYING APPARATUS

Alfred L. Browne, South Orange, N. J.

Application June 27, 1933, Serial No. 677,813

3 Claims. (Cl. 237—78)

This invention relates to humidifiers. More specifically, the invention relates to humidifying devices for use in connection with hot-water or steam heating systems.

5 One of the objects of the invention is to provide a comparatively small humidifying device which, when attached to a radiator, will generate and supply a large quantity of water vapor.

Another object is to provide a humidifying device that directs its discharged water vapor into the hot air stream passing through or from a radiator so that objectionable condensation of the water vapor is prevented.

10 Another object is to provide a humidifying device in which the quantity of liquid evaporated may be readily controlled at will.

15 Other objects and advantages will appear as the invention is hereinafter disclosed.

Referring to the drawings, which illustrate 20 what I now consider to be preferred embodiments of the invention:

Fig. 1 is a sectional elevation of one form of my humidifier particularly adapted to be supplied with water from the usual water main.

25 Fig. 2 is an enlarged elevation of a part of the control mechanism shown in Fig. 1.

Fig. 3 is an enlarged fragmentary detail elevation, partly in section, of another part of the control mechanism shown in Fig. 1.

30 Fig. 3a is a top plan view of the tube or pipe 17 shown in Fig. 3.

Fig. 4 is a top plan view of the part shown in Fig. 2.

Fig. 5 is a sectional elevation of an automatic 35 water-supply valve which may be used in connection with the humidifier shown in Fig. 1.

Fig. 6 is a view similar to Fig. 1 but illustrating a modified form of the humidifier adapted to be employed when it is not desired to supply water 40 thereto from a water main as in Fig. 1.

Fig. 7 is a sectional plan view taken on the line 1—1 of Fig. 6.

Fig. 8 is an enlarged detail sectional elevation 45 of a part of the control mechanism shown in Fig. 6.

The humidifier shown in Fig. 1 comprises a casing 10 having an externally threaded hub 9 adapted to be screwed into the top nipple port or the bottom nipple port of an end section of a radiator, 50 of a type commonly used in heating dwellings or other buildings, after the customary plug has been removed. If the radiator (not shown) is of the hot-water type, the hub 9 is preferably screwed into the top nipple port and if the radiator is of the steam type, the hub 9 is preferably 55

screwed into the bottom nipple port. The hub 9 is drilled to receive the open end of a tube 11 of copper, brass, or other metal having high heat conductivity. The open end of the tube is soldered or otherwise suitably secured within the bore 5 of the hub 9 and the tube 11 is sealed at its other end by a cap 8 soldered or otherwise suitably secured thereto. It will be seen that the tube 11 will be inside the radiator when the hub 9 has been screwed into the nipple port as described 10 above. The tube 11, when supplied with water, serves as an evaporating tube, receiving heat from the hot fluid within the radiator and thereby evaporating water within the tube. The tube 11 receives water from the casing 10 and discharges 15 vapor into the casing 10. The means for supplying water to the casing 10 will presently be described.

The vapor, as stated, passes from the tube 11 into the casing 10. The casing 10 is provided 20 with a cover or lid 12 having a spout 14 through the outer open end of which the vapor is discharged. The spout 14 directs the discharged water vapor into the high velocity heated air stream which passes upwardly from the radiator. 25 If the humidifier is connected to the bottom nipple port of a radiator the spout 14 is so shaped or bent as to direct the discharged water vapor into the hot air stream passing upwardly through the radiator. In either case, by directing the 30 water vapor discharge into the hot air stream, objectionable condensation of the water vapor upon the windows, window-frames, walls, curtains, etc. is prevented.

Water is supplied to the casing 10 (Fig. 1) 35 through a supply pipe 18 which passes through, and is soldered or otherwise suitably secured to, the bottom of the casing 10. One end of the pipe 18 is inside the casing 10 and the other end is connected to the nearest available water supply 40 pipe (not shown).

I provide means for automatically maintaining the water within the casing 10, and consequently that within the evaporating tube 11, at a desired level, which level may be selected or adjusted at 45 will. For these purposes the humidifier is shown provided with a drain pipe 17 which terminates at its upper end within the casing 10, passes through the bottom of the casing, being soldered or otherwise suitably secured thereto, and discharges at its lower end into the nearest sink 50 or sewer drain. The upper end of the drain pipe 17 is provided with a vertical slot 17s (see Fig. 3) cut through its wall. A cap or sleeve 16 surrounds and snugly fits the slotted upper end of 55

the drain pipe. The sleeve 16 (see Fig. 2) is provided with a diagonally extending or curved slot 16s cut through its wall and adapted to cooperate with the slot 17s of the pipe 17 to control the 5 level of the water in the casing 10 according to the relative angular positions of the pipe 17 and sleeve 16. If the sleeve 16 is in such position with respect to the pipe 17 that the upper ends of the slots 16s and 17s are in register, the water 10 level in the casing 10 will be maintained comparatively high, whereas if the sleeve 16 is rotated on the pipe 17 so as to cause the bottom ends of the slots 16s and 17s to register, the water level will be maintained comparatively low. 15 Intermediate these two positions of relative adjustments the slots 16s and 17s may be caused to register at different desired points so that the water level is controllable by rotating the sleeve 16 about the pipe 17. The top or cap portion 20 of the sleeve 16 is provided with holes 16h (see Fig. 4) through which water may flow from the casing 10 into the drain pipe 17, so that in the event that the slots 16s and 17s are not in register at all, or the water level tends to rise above 25 the top of the sleeve 16, the water would then exit from the casing 10 through the holes 16h and be prevented from rising further. It will be understood of course that the parts are so designed and the supply of water through the 30 supply pipe 18 is so controlled, as by means of a needle valve or the like (not shown) therein, that the rate of water supply will not exceed the capacity of the drain pipe 17 and its appurte- nances to carry the surplus water off.

35 Means are provided for turning the sleeve 16 about the pipe 17 and thereby controlling or adjusting the water level within the casing 10 and evaporator tube 11. These means comprise a rod 15 which is square in cross-section and which 40 extends at its lower end through a square hole (see Fig. 4) 15h in the cap or upper part of the sleeve 16 and which is journaled for rotation in, but restrained against axial longitudinal movement with respect to, the lid or cover 12 of the 45 casing 10. The outer or upper end of the rod 15 has secured thereto a knurled knob 13 by which it may be turned and thereby turn the sleeve 16 on the pipe 17.

To improve the sightliness of the humidifier, 50 the otherwise exposed parts of the supply pipe 18 and the drain pipe 17 may be concealed by a tube 19, the upper end of which fits the bottom of the casing 10 as shown, and the lower end of which terminates at the floor.

55 By controlling or adjusting the water level within the casing 10 and the evaporating tube 11, as above described, the amount of water vapor generated at any given temperature to which the tube 11 is subjected, may be controlled or 60 selectively adjusted.

The capacity of the humidifier is determined by the diameter and length of the evaporating tube 11. The length of the tube 11 is determined by the number of sections in the particular radiator to which the humidifier is applied. The diameter of the evaporating tube 11 is determined by the size of the nipple port in the particular radiator to which the humidifier is applied. The capacity of the device may be accurately expressed in water vapor evaporated 70 per hour, in unit lengths and diameters of evaporating tube 11, per pounds of steam available, or temperature of water surrounding the tube 11.

In Fig. 5 I have shown an automatic thermo- 75 static valve which may be inserted in the supply

pipe 18 between the humidifier and the source of water supply, for automatically shutting off the supply of water to the humidifier when the radiator, or other device to which the humidifier is connected, is cold. In this way waste of water 5 may be prevented. The device shown in Fig. 5 comprises a casing 20 provided with a strap 21 by which the casing is secured to the nearest bare pipe that supplies steam or other heating fluid to the radiator to which the particular humidifier is applied. When the steam or other heating fluid is cut off from the radiator, the pipe to which the casing 20 is secured becomes cold and its contained thermostat closes a valve in the water supply line 18. The thermostat 21 is secured to the detachable bottom 24 of the casing 20 and to the lower end of the valve stem or rod 22. The upper end of the valve stem 22 is provided with a valve head 23 which cooperates with a valve seat in the partition or septum of 25 the casing 20 between the water inlet and outlet ports. A packing gland nut 25 serves to impede entrance of water into the chamber of the casing 20 containing the thermostat. While it is intended that no water shall enter the last mentioned chamber, nevertheless the wall of the casing 20 is provided with a water escape or drain orifice 26 so that any water passing through the gland nut will not accumulate within the chamber surrounding the thermostat. It is important 30 that the thermostat shall not be surrounded by water as the exertion of water pressure upon the thermostat would upset the balance or setting of the thermostat.

When the pipe upon which the casing 20 is 35 mounted, by means of the strap 21, becomes cold, the thermostat 21 closes the valve 23 and thereby shuts off the supply of water to the humidifier. When the pipe upon which the casing 20 is mounted becomes hot, the thermostat 21 opens 40 the valve 23 and permits flow of water through the supply pipe 18 to the humidifier.

In Fig. 6 the parts 108, 109, 111, 112, 114, correspond respectively to the parts 8, 9, 11, 12, 14, in Fig. 1 and need not be further described. It 45 will be noted that the lid or cover 112 is provided with a knob 113 by which it may be lifted from the casing 110.

The casing 110 differs in certain respects from the casing 10 of Fig. 1. The casing 110 has a 50 septum or web 121 that provides the main chamber having the lid 112 and a supplemental cylindrical chamber 115, which two chambers communicate through the channel 150 below the web 121.

A jar or water reservoir 117 is provided at its lower end with a screw threaded sleeve 120 which has an annular shoulder for causing the closure 160 to be gripped firmly against the edge of the mouth of the jar to seal it, a compressible washer or gasket 170 being provided to make the seal effective. The lower end of the sleeve 120 is received by a cylindrical opening provided in the upper end of the chamber 115. A tube 119 extends from within the jar 117 through the closure 65 160 and into the chamber 115, when the parts are in the position shown in Fig. 6. The tube 119 is soldered or otherwise suitably secured to closure 160 so as to prevent escape of water around the tube. A second tube 118 likewise passes 70 through the closure 160 and is likewise secured thereto. The tube 118 is, in effect, extensible as by means of a telescoping portion 118a; a gland nut 200 and packing 201 being provided at the upper end of the tubular portion 118a so as to 75

permit relative sliding movement of the tube sections 118, 118a while maintaining an air tight joint. An air inlet port 115a is provided in the wall of the chamber.

5 In operation, the casing 110 and tube 111 are filled with water to about the desired level. The jar 117 is removed and is filled with water and the parts 120 and 160 screwed in place on the jar. The jar is then inverted and the lower end of the 10 sleeve inserted into the chamber 115 (see Fig. 6). When the water level falls, due to evaporation, below the lower end of the tube 118a, air enters the latter and passes upwardly into the jar 117, thereby permitting water to flow from the jar 15 117, through the tube 119, into the chamber 115, until the water level rises sufficiently to seal the lower end of the tube 118a, at which time flow of water from the jar 117 ceases. In this manner the water level is automatically maintained 20 in the casing 110 and evaporating tube 111 (so long as there is water within the jar 117) at a height fixed by the lower end of the tube 118a. By sliding the tube 118a on the tube 118, the position at which the water level shall be automatically 25 maintained in the tube 111 and casing 110, may be adjusted.

The septum 121 and constricted construction of the casing 110 (see Fig. 7) serve to prevent the water in the cylindrical chamber 115 from 30 heating and boiling due to steam present in the other portion of the casing 110.

While the humidifiers herein disclosed are primarily designed for radiators using steam, it may be employed also in closed hot water systems 35 in which the temperature of the water is 212° F. or more. Also, while the humidifiers are particularly adapted to be inserted into radiators, i. e. with the evaporating tube 11 or 111 inserted into a radiator, they may also be employed in combination with pipes that convey 40 heating fluid, tanks containing heating fluid, etc.

In accordance with the provisions of the patent 45 statutes, I have herein described the principle of operation of my invention, together with the apparatus which I now consider to represent the best embodiments thereof, but I desire to have it understood that the apparatus disclosed is only 50 illustrative and that the invention can be carried out by other means. Also, while it is designed to use the various features and elements in the combinations and relations described, some of these may be altered and others omitted and some of the features of each modification

may be embodied in the others without interfering with the more general results outlined, and the invention extends to such use within the scope of the appended claims.

What I claim is:

1. A humidifier comprising in combination, a casing having a portion for insertion into an opening of a steam radiator, and an evaporating tube secured to said casing to receive therefrom liquid to be evaporated and to discharge vapor so produced into said casing, the said evaporating tube being connected to said casing so as to extend horizontally into a radiator when the casing is connected to the latter, the said evaporating tube being sealed with respect to a steam radiator 15 when inserted therein, and said casing having a port for discharging vapor to atmosphere, and means for maintaining the liquid within the evaporating tube at a desired predetermined level below the top of said tube. 20

2. A humidifier comprising in combination, a casing having a portion for insertion into an opening of a steam radiator, and an evaporating tube secured to said casing to receive therefrom liquid to be evaporated and to discharge vapor 25 so produced into said casing, the said evaporating tube being connected to said casing so as to extend horizontally into a radiator when the casing is connected to the latter, the said evaporating tube being sealed with respect to a steam radiator 30 when inserted therein, and said casing having a port for discharging vapor to atmosphere, and adjustable means for maintaining the liquid within the evaporating tube at a desired predetermined level below the top of said tube. 35

3. A humidifier comprising in combination, a casing having a portion for insertion into an opening of a steam radiator, and an evaporating tube secured to said casing to receive therefrom liquid to be evaporated and to discharge vapor 40 so produced into said casing, the said evaporating tube being connected to said casing so as to extend horizontally into a radiator when the casing is connected to the latter, the said evaporating tube being sealed with respect to a steam 45 radiator when inserted therein, and said casing having a port for discharging vapor to atmosphere, means for connecting the casing to a fixed supply of water, and automatic means provided to feed water from said fixed supply of 50 water into said casing at a constant level below the top of said tube.

ALFRED L. BROWNE.
